NUTCRACKER

Filed Nov. 12, 1929

Inventor

E. R. Conklin

By John Boyle Jr.

Attorney

UNITED STATES PATENT OFFICE

EDWARD R. CONKLIN, OF FERRIDAY, LOUISIANA

NUTCRACKER

Application filed November 12, 1929. Serial No. 406,650.

My invention relates to a nut cracker that can be readily adjusted to crack nuts of different sizes, that will be efficient in use and can be cheaply manufactured from stamped metal parts.

Referring to the drawing for a more complete disclosure of the invention

Fig. 1 is a front elevation.

Fig. 2 is a vertical section.

Fig. 3 is a back elevation.

Fig. 4 is a section on line 4—4 of Figs. 1 and 2.

The implement is provided with a stationary jaw 10 having flanges 11 and a movable jaw 12 with a depression 13 in its face for engagement with the end of a nut 14, the said flanges holding the upper end of the nut in proper position.

The lower end of the standard 15 is bent over at 16 and provides supports for the pins 17 to which are pivoted the lower ends of the links 18. The movable jaw 12 is formed from a plate 22 bent over at its upper end 19 and provides supports for pins 20 to which are pivoted the upper ends of handles 21, the said handles being pivoted intermediate their ends to the links 18.

The plate 22 fits between and is guided by the flanges 24 of the standard 15. The standard 15 also carries pins 25 which engage slots 26 to limit the reciprocating movement of the plate 22.

Coil springs 27 surrounding the pins 17 serve to normally keep the sliding jaw 12 in its most open position.

For readily adjusting the jaws to fit different size nuts, the standard 15 is provided with ratchet teeth 28 for engagement with a spring pressed pawl 29 pivoted to the back of the extension member 30 which carries the stationary jaw 10. For limiting the adjustment, slots 31 are provided in the extension member 30 which engages with the aforesaid pins 25 carried by the standard 15.

In operation, the nut will be placed in position with one hand, the other hand squeezing together the handles 21. Pressure will be applied to the nut sufficient to crack it and when cracked the movable jaw will be in final position.

To adjust the distance between jaws, it is merely necessary to press them together to lessen the distance, the pawl riding over the ratchet. To increase the distance between jaws the pawl must be first lifted out of engagement with the ratchet.

From the above description it is clear that I have produced a nut cracker that is compact, made of few parts that can be cheaply manufactured and easily adjusted and while I have particularly described the preferred construction, reference is to be had to the appended claims rather than to the foregoing description to indicate the scope of the invention.

Therefore what I claim as new and desire to secure by Letters Patent is:

1. A nut cracker provided with a stationary jaw and a movable jaw, operating levers pivoted to the movable jaw, and link-connected to the stationary jaw, the said stationary jaw being formed from a plate with a bent over end and flanges on the side to hold the nut in place, the movable jaw formed from a plate with a bent over end and a depression therein to fit the end of the nut.

2. A nut cracker provided with a stationary jaw and a movable jaw, operating levers pivoted to the movable jaw, a standard to which the operating levers are link-connected, bolts carried by the standard, a plate carried by the movable jaw and engaging the bolts to limit the movement of the movable jaw.

3. A nut cracker provided with a stationary jaw and a movable jaw, operating levers pivoted to the movable jaw, a standard to which the operating levers are link connected, bolts carried by the standard, a plate forming a part of the movable jaw and provided with slots engaging the said bolts, a ratchet carried by the standard, an extension member forming a part of the stationary jaw and a pawl carried by the said member for engaging the said ratchet.

In testimony whereof I affix my signature.

EDWARD R. CONKLIN.
